SORTING MACHINE

Waldemar Ayres and Gilbert N. Fryer, Binghamton, N. Y., assignors to International Business Machines Corp., New York, N. Y., a corporation of New York

Application October 20, 1934, Serial No. 749,147

3 Claims. (Cl. 209—111)

This invention relates to means for sorting addressed letters or envelopes according to the various postal districts to which they are to be sent.

5 Mail which is sent out in large quantities such as circular letters or advertising matter is delivered in bulk to the various post offices where it is separated by clerks according to districts. This sorting is done manually and each letter is handled and read separately.

The object of the present invention is to devise means to perform this sorting automatically and thus much more rapidly than it is now possible to do it.

15 According to the invention a code indication is stamped or printed on the envelope and is adapted to be analyzed by a machine having light sensitive elements and the envelope sorted in accordance with the code markings.

20 In illustrating the invention, the portion of the envelope to be sensed is shown as including six marked off areas or squares. Several of the squares may be filled in with ink so as to vary their light reflecting properties. In addressing an envelope, the operator by the depression of appropriate keys on the machine, may fill in the blank squares in accordance with the district to which the envelope is addressed. Or if addressing stencils are used, the stencils will cause the code 25 to be printed on the envelope. When a quantity of such mail is delivered to the post office, the letters will be placed in the sorting machine and run through, the machine feeding one at a time. Each letter is carried to an analyzing station where 30 the control area is analyzed by a light scanning device, and sorting elements controlled in accordance with the combination of spots marked upon the envelope.

The envelope is then carried away from the 35 analyzing station and passes over sorting chute blades until it reaches the particular blade representing the district marked upon the envelope. At this point electric circuits are operated to bring about a separation of the chute blades to cause 40 the envelope to pass between two adjacent blades and to be guided by such blade into the pocket representing the particular postal district.

Referring to the drawings:

Fig. 1 is a wiring diagram illustrating the manner in which the machine operates.

Fig. 2 is an enlarged detail of the ends of the chute blades and the means for controlling their operation.

Fig. 3 is a sectional detail taken on line 3—3 of 55 Fig. 2.

Fig. 4 is an envelope marked to control the operation of the machine to effect sorting of the envelope in accordance with the markings thereon.

In the drawings, the envelope 1 is shown as 5 having an area made up of six squares 2, certain ones of which are filled in as at 3. A stack of letters so marked is placed in the hopper 4 and fed one at a time toward the right by a picker 5 to the position 1a. The sensing mechanism is 10 contained in the dotted position indicated at 7. After the envelope has been analyzed, it is fed from the sensing position by a picker 5a to the endless friction belt 8 which will carry it over the tops of a plurality of chute blades 9. The 15 letter will depress or cam downwardly each of the chute blades in succession as it moves toward the right. All of the chute blades rest against the lower surface of a plate 10 mounted on parallel motion arms 11.

The plate is normally in the position of Figs. 1 and 2 but will be raised by energization of electromagnet 12. This will permit the blades, which press resiliently upward, to follow the plate. Such blades as have been depressed by the envelope, however, will continue to be held down, thus creating a path between the blades for the envelope to follow. The paths between the chute blades lead to separate receptacles 13, one for each postal district.

30 The sensing device contained in the enclosure 7 (Fig. 1) includes a light source 14 adapted to project a beam of light to the field 2 on the envelope from which it is reflected through perforations 15, 15a in a scanning disk 16. The light 35 passing through the perforations in the scanning disk falls upon a light sensitive tube 17 which controls the flow of current through a grid glow tube 18. The scanning disk 16 is mounted on a shaft 19 which also carries contact arm 20 wiping 40 successively over several contact segments 21. The perforations 15 and 15a in the scanning disk are so located that the perforation 15 first permits light to be reflected from the upper left hand square in field 2, then the middle left hand square 45 and then the lower left hand square. The perforation 15a then comes into play and permits light to be reflected from the upper right hand square, then the middle right hand square and then the lower right hand square. As the perforations in the scanning disk pass these squares to permit light to fall from the light sensitive tube 17, contact arm 20 is passing synchronously over the several contact segments 21. The light falling upon the tube as the arm 20 passes over suc- 50 55

cessive segments 21 controls the passage of current through the tube 18 and through the respective segments 21.

In other words, when the light is reflected from the spot on the envelope, no current will pass through the tube 18, but when a dark spot is scanned, the light reflected diminishes and current will pass through the tube 18, coming from the negative side of the line 22a, then through the arm 20 to the respective segment 21, through wire 23, through an electromagnet 24, wire 25, cam operated contacts 26 and back to the other side of the line 22.

The energization of electromagnet 24 closes contacts 27 and thus forms a holding circuit for the electromagnet from the line 22a through wire 28, contacts 27, armature 29, magnet 24, contacts 26 to the line 22.

There are six magnets 24, designated 24 to 24e, corresponding to the six segments 21 and the six spots in the field 2. One or more of these magnets 24 will be energized depending upon the arrangement of dark areas in the field 2. Each of the magnets 24, besides closing its own holding circuit at contact 27, also serves to close certain other contacts 30 and to open certain normally closed contacts 31. The setting of the contacts 30, 31 in the various combinations by one or more of magnets 24-24e, provides a path for current from the positive line 22 through wire 28a, contacts 30, 31 according to their setting, to wires 32, a particular one of the several chute blades 9, plate 10, magnet 33, to line 22a. All of the chute blades 9 normally engage plate 10 so that whichever one serves as a conductor for a particular set-up, breaks the circuit when the envelope depresses it, and causes the plate, which serves as an armature, to be raised. All of the chute blades to the right of the envelope at this moment, will follow the upward movement of the plate 10 so that as the envelope continues to be fed toward the right, it will be turned downwardly by the next chute blade and will follow the path between the blades and fall into a corresponding receptacle 13.

As soon as one envelope has opened the circuit through the chute blades and plate 10, the machine will be ready to analyze the next envelope to effect the next setting up of contacts 30, 31.

The starting of this next cycle is effected at the same time that magnet 12 is energized. It is done by the closing of contacts 40 which are normally held open while the electromagnet 33 is energized and closed when magnet 33 is deenergized. The closure of these contacts now closes a circuit through a clutch magnet 41 which thereupon attracts its armature 41a which acts as a latch to a one revolution clutch. This clutches the shaft 43 to the normal operating shaft 44. The clutch is adapted to cause the shaft 43 to turn one revolution and then stop. During the first part of this revolution, the scanning shaft 19 is operated through gears 45, 46, and this serves to analyze the envelope which is standing in position 1a. The electromagnets 24 and contacts 27, 30, 31 are then set in accordance with the reading taken from the envelope. During the next part of the revolution, the cam 47 operates the follower arm 48 which is connected to the plate 49 carrying the pickers 5, 5a. This operation feeds the envelope from position 1a to the

feed belts 8a on the rollers 8, and simultaneously feeds the next envelope from the magazine 4 into the position 1a. The pickers 5, 5a are returned to the normal position as shown at which point the clutch 42 releases the shaft 43, leaving the scanning and feeding mechanism in their normal positions until the envelope now being fed by belts 8a depresses the particular chute blade 9 through which the current is passing. This will break the circuit through magnet 33, once more causing magnet 12 to operate to feed the envelope into the proper path leading to the receptacles 13, and also causing the magnet 41 to become energized to start the next scanning and feeding operation.

In order to register the letter in position for scanning, a stop 50 may be provided. The stop is normally up in position. A magnet 51 is adapted to be energized to remove the stop from the path of the letter when it is to be fed, and de-energized to let the stop return to position in time to cooperate with the next letter. A cam 52 on shaft 19 is timed to open and close the circuit through the magnet at the proper times.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination, a supply hopper for envelopes, an analyzing station, light sensitive analyzing means at said station, means for feeding envelopes from the hopper to the station, a plurality of receptacles, means for selectively directing envelopes into said receptacles, said means being controlled by said analyzing means, and means operated by an envelope being fed into the receptacles for causing operation of the analyzing means to analyze the next envelope.

2. In an envelope sorting machine, means for analyzing a combinational code area on an envelope, a plurality of contacts selectively set by said analyzing means to selectively close one of a plurality of sorting circuits, said circuits including guiding chute blades adapted to be displaced by an envelope being fed to break the circuit, means operated when the circuit is broken for causing the envelope to be directed into a path between the chute blades, and a plurality of receptacles associated with said chute blades to receive the envelopes.

3. In a sorting machine, a plurality of sorting stations, a plurality of guides for guiding articles to be sorted to said stations, an electrically controlled member for controlling the positions of said guides, said member being controlled by an electric circuit passing through one of the guides as a conductor, means for feeding an article to be sorted with respect to the guides, the article being adapted to move the guides and thus break the electric circuit therethrough to cause operation of the electrically controlled member.
